LANDING-GEAR FOR FLYING-MACHINES.

1,342,138.

Specification of Letters Patent.

Patented June 1, 1920.

Application filed July 30, 1919. Serial No. 314,294.

To all whom it may concern:

Be it known that I, MAXIMILLIAN F. STUPAR, a citizen of the United States, residing at Buffalo, in the county of Erie and State of New York, have invented a new and useful Improvement in Landing-Gears for Flying-Machines, of which the following is a specification.

This invention relates to landing gears for flying machines.

Ordinarily aeroplanes are equipped with a single pair of ground wheels disposed at the opposite ends of a transverse axle or shaft which is movably mounted on the landing gear frame and is connected thereto by elastic bands or springs which afford a resilient support for the machine and act to cushion the shocks incident to making landings. The possible variation in the position of the wheel axle or shaft forwardly or rearwardly with reference to the center of weight of the machine is comparatively limited. If the wheels are too far rearward they are apt to cause the machine to nose over or tip forwardly in making a landing, especially when landing on soft or uneven ground. On the other hand, if the wheels are set too far forwardly, the lifting effect of the landing gear springs on the rear end or tail of the machine is so reduced as to magnify the drag of the tail on the ground and greatly increase the difficulty of rising from the ground. In any case it is a serious problem to provide, in a single axle construction, a sufficient number of springs or elastic bands to give the requisite spring support for a large, heavy machine without unduly complicating the construction and increasing the wind resistance.

The object of this invention is to produce a practical and efficient landing gear for flying machines which will overcome the above noted objections and provide an adequate and desirable resilient support for large, heavy machines.

In the accompanying drawings:

Figure 1 is a fragmentary side elevation of a landing gear embodying the invention.

Fig. 2 is a plan view thereof.

Fig. 3 is a transverse section thereof on line 3—3, Fig. 1.

Fig. 4 is a perspective view, on a reduced scale, showing the arrangement of two like landing gears on a machine.

A represents the landing gear frame, or

depending portion of the main frame of a flying machine on which the ground wheels are mounted. This frame may be of any suitable construction, having the necessary strength, rigidity and lightness. The frame 60 shown has a substantially vertical front post or member 10, a brace 11 which inclines upwardly and rearwardly from the lower portion of the front post 10, and a lower end portion which is preferably extended fore 65 and aft of the machine so as to form a relatively long, narrow base 12 for the connection of the ground wheels 13. The post and brace are of the usual stream-line form in cross-section. There are preferably four 70 ground wheels arranged in two pairs at the front and rear ends of a suitable wheel support or carriage. The wheel carriage shown is composed of two parallel side bars 14 which extend lengthwise at opposite 75 sides of the base 12 of the landing gear frame and are connected at their front and rear ends by transverse shafts or axles 15 on the ends of which the ground wheels are suitably mounted or journaled. The wheel 80 carriage is resiliently connected to the base of the landing gear frame by elastic bands or springs which permit the wheel carriage to yield upwardly relative to the landing gear frame, or the latter to yield downwardly relatively to the wheel carriage. Preferably a series of cross rods 17 connecting the side bars 14 of the wheel carriage extend transversely through vertically elongated slots 18 in the base of the landing gear frame, and elastic or spring bands or loops 19 attached to the projecting ends of the cross rods 17 pass under and engage the lower edge of the base 12 of the landing gear frame. A group of these bands are 85 usually connected to each cross rod. Hooks or heads are preferably provided on the projecting ends of the cross rods 17 to prevent the disengagement of the bands from the rods, and the lower edge of the landing gear frame is preferably provided with cross ribs or projections 20 which confine the elastic bands and prevent them from shifting on or disengagement from the base 90 of the landing gear frame. 100

105

When the wheels rest on the ground, the landing gear frame and the weight of the machine carried thereby are thus suspended from the wheel carriage by a plurality of elastic bands or loops which are located at 110

intervals along the length of the carriage and yieldingly support the machine from the carriage and permit it to yield downwardly under the weight relatively to the 5 wheel carriage. The wheels located at the opposite ends of the relatively long wheel carriage are spaced a considerable distance apart lengthwise of the machine or in the direction of flight, and the front and rear 10 wheels can be thus disposed respectively in front of and in rear of the center of weight of the machine. The wheel carriage can move bodily up and down relatively to the landing gear frame while maintaining a substantially horizontal position, so that when 15 the center of weight of the machine is substantially over the center of the carriage the front and rear wheels have substantially equal supporting effect. In addition, however, the described resilient connections 20 between the wheel carriage and the landing gear frame permit either the front or rear end of the wheel carriage to yield relatively to the landing gear frame to a greater extent than the opposite end. Therefore, when 25 the machine is making a landing, if the front wheels first strike the ground they can yield upwardly and cushion the shock more or less until the rear wheels strike the ground 30 and cooperate with the front wheels in carrying the machine, the carriage being permitted to yield bodily horizontally while remaining horizontal or to tip up at its front or rear end to equalize the weight on the 35 front and rear wheels and balance the machine. The front wheels can be located far enough forward to practically eliminate the possibility of the machine nosing over and thus being damaged or injuring the occupants in making landings. On the other 40 hand, if the machine, in landing, is at such an inclination that the rear wheels first strike the ground, these can yield and cushion the shock more or less and hold the tail 45 of the machine off the ground until the machine settles on all of the wheels. In rising from the ground the rear wheels, being located in rear of the center of weight of the machine, have a much greater effect in lifting 50 and holding the tail of the machine off of the ground than wheels located farther forward in the more usual arrangement, and the machine can therefore rise more readily.

By the described construction also, the resilient supports for the machine are distributed over a considerable distance lengthwise of the machine, so that an adequate supporting capacity is provided without an undue increase in the wind resistance and 55 without the objectionable bunching of a large number of elastic bands at one place.

A machine can be equipped with a single wheel carriage resiliently mounted as described and having the wheels appropriately

spaced to give the requisite lateral stability 6 to the machine, or in the case of very large machines two such carriages can be used at opposite sides of the center of the machine, as indicated in Fig. 4.

I claim as my invention:

1. A landing gear for flying machines, comprising a frame having a narrow base portion extending lengthwise of the machine, a wheel support extending lengthwise of said frame, ground wheels at the front 7 and rear portions of said wheel support, cross rods extending from said wheel support through elongated slots in said frame, and elastic bands passing under said frame base and attached to said cross rods. 80

2. A landing gear for flying machines, comprising a frame having a relatively long narrow base extending lengthwise of the machine, a vertically movable wheel carriage comprising connected side bars extending lengthwise at opposite sides of and close to said frame base whereby said carriage is guided in its movements by said frame base, ground wheels mounted on the front and rear portions of said carriage, 90 and resilient connections between said carriage and frame base disposed at a plurality of points lengthwise of said carriage and permitting the carriage to yield relatively to said frame base. 95

3. A landing gear for flying machines, comprising a frame having a relatively long narrow base extending lengthwise of the machine, a vertically movable wheel carriage comprising connected side bars extending lengthwise at opposite sides of and close to said frame base between the upper and lower extremities thereof, ground wheels mounted on the front and rear portions of said carriage, and springs yieldingly supporting said base from said carriage at a plurality of points lengthwise of said carriage. 100

4. A landing gear for flying machines, comprising a frame having a relatively long narrow base extending lengthwise of the machine, a vertically movable wheel carriage comprising side bars extending lengthwise at opposite sides of and close to said frame base whereby said carriage is guided in its movements by said frame base, cross rods connecting said carriage side bars and extending through elongated slots in said frame base, and springs yieldingly supporting said base from said carriage at a plurality of points lengthwise of said carriage. 110

Witness my hand, this 28th day of July, 1919.

MAXIMILLIAN F. STUPAR.
